UNITED STATES PATENT OFFICE.

CHARLES HENRY WORSNOP, OF HALIFAX, ENGLAND.

DESIGN FOR SHEET-METAL STOCK FOR MAKING CELLS OR CONTAINERS FOR ELECTRICAL ACCUMULATORS.

59,804.

Specification for Design.

Patented Nov. 22, 1921.

Application filed February 28, 1921. Serial No. 448,611. Term of patent 14 years.

To all whom it may concern:

Be it known that I, CHARLES HENRY WORSNOP, a subject of King George V of Great Britain, residing at Halifax, in the county of York, England, have invented a new, original, and ornamental Design for Sheet-Metal Stock for Making Cells or Containers for Electrical Accumulators, of which the following is a specification, reference being had to the accompanying drawing, forming part thereof.

Figure 1 is a face view and Fig. 2 a sectional view of a portion of sheet metal stock for making cells or containers for electrical accumulators, having the design applied.

The essential feature of the design consists in providing the sheet metal with concavo-convex recesses 3 of circular form. These recesses are spaced at substantially equal distances apart, and are arranged alternately, the concave sides of one half of the recesses being arranged on one side of the sheet, and the concave sides of the remaining recesses being arranged on the other side of the sheet.

I claim:—

The ornamental design for sheet metal stock for making cells or containers for electrical accumulators, as shown and described.

CHARLES HENRY WORSNOP.
